UNITED STATES PATENT OFFICE.

ELI PACKER, OF DES MOINES, IOWA.

HAMMER AND NAIL-HOLDER.

SPECIFICATION forming part of Letters Patent No. 650,414, dated May 29, 1900.

Application filed February 1, 1900. Serial No. 3,596. (No model.)

To all whom it may concern:

Be it known that I, ELI PACKER, a citizen of the United States, residing at Des Moines, in the county of Polk and State of Iowa, have 5 invented a new and useful Hammer and Nail-Holder, of which the following is a specification.

The object of this invention is to provide improved means for receiving and retaining 10 a nail adjacent to the poll of a hammer for the purpose of starting said nail into a board or other wooden object by the use of one hand only.

My invention consists in the combination, 15 with a hammer, of a spring clamp, jaw, or holding device arranged upon or formed integrally with one side of the poll of said hammer and so shaped as to receive and retain a nail at right angles to the handle of the hammer and projecting beyond the face thereof.

My invention consists, further, in the construction, arrangement, and combination of 20 elements hereinafter set forth, pointed out in my claims, and illustrated by the accompanying drawings, in which—

Figure 1 is a side elevation of a hammer, showing a nail mounted therein as required for practical use, a portion of the handle being broken away. Fig. 2 is a plane, partly 25 in section, on the indicated line 2 2 of Fig. 1. Fig. 3 is an elevation of the hammer at right angles to Fig. 1. Fig. 4 is an elevation of a hammer, showing the nail-holding device separately formed and attached thereto. Figs. 30 5 and 6 are detail elevations of the nail-holding device detached from the hammer. Fig. 7 is an enlarged face view, partly in section, of the nail-holding device shown in Figs. 5 and 6. Fig. 8 is a transverse sectional view 35 40 on the line x x of Fig. 7, showing a nail clamped between the shoulder on the inner end of a spring-actuated detent and a setscrew as required to hold a nail.

In the construction of the device as shown 45 in Figs. 1, 2, and 3 the numeral 10 designates a hammer of ordinary size and form of the class known as "claw-hammers" and provided with a handle 11. Ears, bosses, or projections 12 13 are formed on and project toward 50 the handle from the poll 10^a of the hammer, and said ears are parallel to each other and spaced apart to form a slot or groove 14.

A boss 15 is formed on and extends from the eye portion of the hammer 10, and a concave seat is formed in said boss. The ear 12 is 55 provided with a transverse hole or bore 16 near its upper end, and the ear 13 is provided with a bore or hole 17 in alignment therewith. The initial and body portions of the bore 17 are of the same diameter as the bore 16; but 60 the terminal portion of said bore 17 is of less diameter than the remainder, thus forming shoulders adjacent the outer surface of the ear 13. An expansive coil - spring 18 is mounted in the main portion of the bore 17 65 and impinges the shoulder thereof at one end. A bolt 19, having a head, is mounted in the bore 17 by longitudinal movement through the bore 16, and the threaded portion of said bolt projects beyond the outer face of the ear 70 13 and is provided with a nut 21, screwed thereon. The end of the spring 18 opposite the shoulder impinges the head 20 of the bolt 19 and presses said head of the bolt into a notch or groove 14, the degree of projection 75 of the bolt into the groove being determined by an adjustment of the nut 21 on the bolt.

In practical use a nail 22 is mounted with the head thereof in the concaved seat of the boss 15, and the body of the nail is pressed 80 into the groove 14 and, contacting with the head 20, moves the bolt longitudinally against the force of the spring 18 into position shown in Fig. 2. The nail is retained by confinement between the spring-pressed head of the 85 bolt and the inner surface of the ear 12. By manual force the hammer may be swung to penetrate the nail into a wooden object, and then by oscillated movement of the hammer said hammer may be withdrawn from the 90 nail and the nail further driven by repeated blows thereon.

In the construction of the device shown in Figs. 4, 5, 6, and 7 the hammer 10^b is of common form, and a screw-seat is formed in one 95 side of the poll thereof. A bracket 23 is mounted on the poll of the hammer and secured thereto by a screw 24, traversing the bracket and entering the seat formed in the poll of the hammer. The bracket 23 is formed 100 with a base 23^a, having a concaved seat opening upwardly therefrom, and the face of said bracket is provided with ears 25 26, rising parallel with each other and spaced apart

- above the base 23^a. A bore or hole 27 is formed in the ear 26, and a hole or bore 28 is formed partially through the ear 26 in alignment with the bore or hole 27 and opening 5 into the groove 29 between said ears. An expansive coil-spring 30 is mounted in the bore 28, and a detent 31 is mounted in the bore and crosses the groove 29. A screw 32 is fitted in the bore 27 and adjustably connected 10 with the inner end of the detent 31 to engage a nail, as clearly shown in Fig. 8, and to engage the inner end of the detent 31 when the nail is removed. It is the function of the set-screw 32 to retain the detent and permit free 15 movement thereof in the bore and also to prevent torsional movement of the detent. A portion of the detent 31 is cut away, forming a shoulder 31^a, opening outwardly, but within the groove 29.
- 20 In practical use the bracket is mounted on the poll of the hammer and a nail placed within its head in the concaved seat of the boss 23^a and its body depressed within the groove 29 and in contact with the shoulder 25 31^a of the detent, to the end that the detent is moved longitudinally against the pressure of the spring 30 until the nail contacts with the plane face of the detent. The nail is re-

tained between the shoulder of the detent and the inner surface of the ear 25 by reason 30 of the pressure of the spring 30 in the bore 28. After the nail is mounted in the bracket the hammer may be swung to penetrate and mount said nail in a wooden object and then be oscillated to release the nail, after which 35 said nail may be driven by repeated blows of the hammer.

I claim as my invention—

1. A hammer having two mating parallel projections extending outward and vertically 40 from the poll and provided with coinciding transverse bores, a spring-actuated detent fitted in one of said bores and means for restricting the longitudinal movement of the detent, arranged and combined to operate in 45 the manner set forth for the purposes stated.

2. The combination of the hammer having a poll, a bracket mounted thereon and formed with a groove and a seat in alignment therewith and a spring-bolt mounted in the bracket 50 and entering the groove therein.

ELI PACKER.
